ROADSIDE SERVICE JACK

John R. Butorac, Hales Corners, Wis., assignor to
Applied Power, Inc., Milwaukee, Wis.

Filed Oct. 24, 1973, Ser. No. 409,163

Term of patent 14 years

Int. Cl. D12—05

U.S. Cl. D12—55

FIG. 1 is a perspective view of a roadside service jack showing my design in a raised position, it being understood that the handle has been broken away in the middle to indicate indeterminate length;

FIG. 2 is an end elevational view thereof in a lowered position;

FIG. 3 is an end elevational view opposite to that shown in FIG. 2;

FIG. 4 is a right side elevational view of FIG. 2;

FIG. 5 is a left side elevational view of FIG. 2;

FIG. 6 is a top plan view of FIG. 2; and

FIG. 7 is a bottom plan view of FIG. 2.

The handle has been omitted from FIGS. 2 through 7 for convenience of illustration.

I claim:

The ornamental design for a roadside service jack, as shown and described.
